United States Patent Office

Des. 183,431

Patented Aug. 26, 1958

183,431

TETHERBALL

David Louis Senne, La Habra, Calif., assignor to W. J. Voit Rubber Corp., Los Angeles, Calif., a corporation of California

Application November 19, 1956, Serial No. 43,817

Term of patent 14 years

(Cl. D34—15)

FIG. 1.

FIG. 2.

FIG. 3.

Fig. 1 is a plan view of a tetherball embodying the invention;

Fig. 2 is a side elevational view of the ball; and
Fig. 3 is a bottom view.

I claim:

The ornamental design for a tetherball, as shown.
